Inventor
John Wood

United States Patent Office.

JOHN WOOD, OF LOWELL, MASSACHUSETTS.

Letters Patent No. 69,148, dated September 24, 1867.

IMPROVED LADIES' WORK-TABLE.

The Schedule referred to in these Letters Patent and making part of the same.

TO ALL WHOM IT MAY CONCERN:

Be it known that I, JOHN WOOD, of Lowell, in the county of Middlesex, and State of Massachusetts, have invented new and useful improvements in Ladies' Work-Tables; and I do hereby declare that the following is a full and exact description thereof, reference being had to the accompanying drawings and to the letters of reference marked thereon.

The nature of my invention consists in providing a work-table with a suitable box or receptacle for receiving sundry articles of work, also a tray divided into numerous apartments, for holding the requisite instruments for the lady's work.

To enable others skilled in the art to make and use my invention I will proceed to describe its construction and operation.

Figure 1 represents a vertical section of my improved work-table.

Figure 2 represents a plan of the tray.

a represents the table; *b*, the cover; *c*, the tray; and *d*, the work-box. *a* represents the table; its outside may be ornamented and finished with carved, inlaid, plain, or perforated work, to accommodate and suit the trade. The form, as shown by the drawings, is of an inverted octagon hollow cone, which is furnished with its requisite feet for support, but can be made round or of any shape that will leave the inside hollow. In the top of the table *a*, a recess is formed for the reception of the tray *c*; below this recess the work-box *d* is formed, which is suitably lined with any desirable material, the cover of this box *d* being the tray *c*. The tray *c*, being made of the required size and shape, with its numerous apartments suitably lined and cushioned, is then placed in the recess. The cover *b*, which forms the top of the table *a*, "when closed," is hung by a hinge on one side, its under side being lined with cloth; its edge, opposite from the hinge, is provided with a suitable lock to fasten down the same. The table *a*, being thus made and finished, is then ready for use, the tray *c* containing the necessary articles and instruments which the ladies require, the box *d* containing the work, and when not used for this purpose the cover *b* is closed down and secured; it then makes an elegant and beautiful article of furniture, and an ornament to the room.

What I claim as my invention, and desire to secure by Letters Patent, is—

A work-table, with tray *c* and box *d*, arranged substantially as described, and for the purposes fully set forth.

JOHN WOOD.
